UNITED STATES PATENT OFFICE.

HENRY HERMANI, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DOUBLE-SEAMING MACHINE.

Application filed December 18, 1920. Serial No. 430,302.

To all whom it may concern:

Be it known that I, HENRY HERMANI, a citizen of the United States, and resident of Baltimore, in the State of Maryland, have 5 invented certain new and useful Improvements in Double-Seaming Machines, of which the following is a specification.

My invention relates to mechanism especially well adapted for connecting, by 10 "seaming," simultaneously, two separate members to a can body, to form a substantially complete can or box.

In a particular embodiment of the invention, it has been devised especially for simultaneously applying to a ring-like body 15 of variable contour, two originally-separate side plates of similar contour, the complete boxes or "cans" so formed being especially suitable for packaging toilet powders and 20 similar commodities, for the reason that the shape of the boxes is readily varied to meet the requirements of the vendors for boxes of different and distinctive shapes. The machine, as explained hereafter, may be easily 25 adapted for the seaming of such differently-shaped containers, by changing or adjusting a very small number of parts, and these changes may be very quickly and simply made.

30 A principal object of the invention, therefore, is to provide simple, efficient and economical seaming mechanism for simultaneously applying two "side" members to a can body.

35 A more particular object is to especially adapt seaming mechanism for operating upon sheet metal parts of forms such as are hereafter described.

40 A further object is to provide mechanism which may be arranged for operation upon containers of different shapes and sizes, by the exchange of very few and simple parts, with simple or no adjustments.

45 While the particular embodiment of the invention here shown and described is especially adapted for the production of containers of the class described, the range of equivalent parts and combinations is not intended to be limited by reason of such adaptation, beyond the limitations expressed in 50 the claims.

The characteristics and advantages of the invention are further sufficiently explained

in connection with the following detail description of an exemplifying structure embodying the invention; and after considering this embodiment, it will be understood that many changes in structure and arrangement may be made within the spirit of the invention. 55

Figure 1 is a view, partly in elevation and partly in section of part of a can-seaming machine embodying the invention, 60

Figure 2 is a similar view, with certain parts in another operative position, 65

Figure 3 is an enlarged sectional detail of a pair of seaming rolls and their carrier,

Figure 4 is a side-elevation of a container of the sort for the production of which the invention is, in this particular embodiment, 70 adapted,

Figure 5 is a face view of a "pattern" cam corresponding to the container of Figure 4,

Figure 6 is a detail, similar to Figure 3, showing a different arrangement or "adjust- 75

ment" of seaming rolls,

Figure 7 is a front elevation, largely dia- 80

grammatic, of sufficient parts of a complete machine, to enable the operation of the seaming mechanism to be understood,

Figure 8 is a side elevation, also dia- 85

grammatic, of Figure 7.

A complete machine, of one available form for the present purpose, is shown in sufficient detail in Figures 1, 2, 7 and 8. It 85 comprises a frame or housing 1, in which is mounted, in suitable bearings, a vertical shaft 2, driven by gears 3 from a horizontal shaft 4, which may be the main drive shaft of the machine. Shaft 4 is connected by 90 sprockets and chain 5 to a shaft 6, and this carries a worm 7, driving worm-gear 8 on shaft 9, which also carries similarly-shaped cams 10. The principal parts of the peripheries of these cams consist of spirals 11, 95 whose ends are connected by short diagonal surfaces 12. Cam rollers 13 running on the cam peripheries are carried by levers 14, fulcrumed at 15, and having their ends 16 located in slots 17 in vertically-sliding plungers 18, mounted in suitable guides in the housing. 100

Plungers 18 have heads 19, the lower faces of which are engaged by rollers 20 carried by arms 21 of seaming-roll positioning bell- 105 cranks 22, fulcrumed at 23 in cam-actuated

slides 24, mounted in guides 25 on the under side of housing 1, to move toward and from the axis of shaft 2.

Each of the slides 24 has on its lower face, 5 guides 30, in which is mounted a seaming-roll carrier 31, so that these carriers may move toward and from the axis of shaft 2 to a certain extent, independently of slides 24. Each roll-carrier has a central channel 10 32, accommodating a movable block 33, provided with a socket 34, engaged by the rounded end 35 of arm 36 of one of bell-crank 22. Each carrier 31 also has a screw 38, provided with a long shank having rotatable bearings in the carrier near its inner 15 and outer ends, and having an exposed head 39 by which it can be rotated. The threaded portion of the screw engages block 33. A spring 40, compressed between arm 36 of each bell-crank and a part of slide 24 normally holds the seaming-roll carrier in retracted position in relation to its slide.

The carriers are periodically advanced in a direction toward the vertical-shaft axis, 25 with relation to slides 24, by cams 10, acting through levers 14, plungers 18, their heads 19, and bell-crank 22, this advance being a relatively slow feeding movement effected by spiral cam faces 11; and then the carriers 30 are quickly retracted by springs 40 as diagonal cam-surfaces 12 pass under rollers 13. The inward limit of the feeding movement may be regulated by rotating screws 38, which has the effect of changing the position 35 of the carrier in relation to its slide 24, in any given position of the slide and head 19.

In any angular position of the bell-cranks, determined by the position of cams 10, the 40 slides 24 may be moved to-and-fro, in accordance with the contour of can bodies which are being seamed, by suitable means described below, and in this movement of the slides, rollers 20 run back and forth on the 45 under faces of heads 19.

Figures 1 to 4 show containers or "cans" C of a kind for the seaming of which the invention, in the present embodiment is especially desirable. Such cans consist mainly 50 of a strip b of sheet metal, which may be joined at one point by a suitable seam, constituting in effect a continuous body, forming two sides, top, and bottom, of the completed can; and two separate plates s, constituting the remaining sides of the 55 complete can, as shown in Figure 4. The central areas a of the side plates are depressed, or "dished," producing a right-angled shoulder k, terminating in a peripheral flange f, 60 the shoulders and flange edges usually having a more or less irregular, non-circular contour, which may be varied greatly, the contour of the body b being in agreement, to produce a great variety of artistically-shaped containers, one of which, involving 65

most of the seaming problems which this invention is intended to meet, is shown in Figure 4. Shoulders k of the side plates fit closely within the margins of the body strip, with flanges f projecting.

To hold and manipulate such a can-assembly for seaming, shaft 2 is provided with a detachable fitting F, comprising a cam body 45 and a plate 46, the periphery of which fits closely within the shoulder k of 70 the upper can-side plate. Coaxially arranged below shaft 2 is another shaft 48, mounted to rotate and reciprocate vertically in suitable bearings (not shown), and provided with suitable manually acted means, 80 such as a pedal (not shown) for effecting its vertical movement. This shaft is provided with a detachable fitting G, which carries a plate 49, of a shape identical with plate 46, fitting within the shoulder of lower 85 can-side s.

Cam body 45 has a cam-groove 50, contoured to agree with the contour of the can-sides, and in this groove are cam-rollers 51, carried by pins 52 connected to extensions 53 of slides 24.

The inward ends of roll-carriers 31 are formed with jaws 55, and in each pair of jaws is a roll-shaft 56, secured for easy detachment by a set-screw 57. On each roll 95 shaft are two seaming rolls 58, which have faces properly formed to engage the edges of can-side flanges f, and by proper pressure and rotation of the can members and rolls, to roll down the flanges upon the edges of 100 the can body, producing rolled seams 60, Figure 3, which unite the side members to the body. The pressure of the rolls is taken by the edges of plates 46 and 49, which are in effect, die-plates, cooperating with the rotary seaming dies 58. The rolls are spaced apart so that they are properly located in relation to the flanges, by suitable means, such as sleeves or washers 62, placed in the roll-shafts between the rolls. The length of 105 these sleeves is appropriate to the distance between the can-flanges determined by the width of the body b, with due regard to the positions of the rolling grooves in the bodies of rolls 58. To properly position the rolls for can bodies of different widths, sleeves 62 may be replaced by longer or shorter ones, as for instance as shown in Figure 6, where sleeve or washer 63 is shorter, bringing the seaming rolls nearer together, for rolling 110 flanges f which are correspondingly closer together, to fit a narrower body b'. Also, since the upper shaft-fitting F is most conveniently fixed against vertical movement, the clamping of narrower cans between die plates 46 and 49 brings the lower can-flange higher up; and the adjustment of distance between the die rolls is therefore made, in the present case, by moving the lower rolls 115 up, the upper rolls remaining in the same 120

125 flanges f which are correspondingly closer together, to fit a narrower body b'. Also, since the upper shaft-fitting F is most conveniently fixed against vertical movement, the clamping of narrower cans between die plates 46 and 49 brings the lower can-flange higher up; and the adjustment of distance between the die rolls is therefore made, in the present case, by moving the lower rolls 130 up, the upper rolls remaining in the same

positions; and other sleeves or washers 65 (Figure 6) are placed between the lower carrier jaws 55 and the lower rolls to properly position them.

5 The roll positioning devices, such as sleeves or washers 62, 63 or 65, may be conveniently identified, in some cases, as "spacers."

In the examples shown, only a moderate 10 range of adjustment is provided for the die seaming rolls; but evidently by making the space between the carrier-jaws wider, and providing sleeves or washers of suitable thickness (it being of course possible to use 15 a number of relatively thin washers to equal the effect of one thick one) any reasonable range of adjustment may be provided for cans of correspondingly varying dimensions.

The machine being properly set up and 20 adjusted for cans of given width and contour, and drive shaft 4 being in motion, shaft 48 and its fitting G are retracted by the operative, and a can assembly placed on the fitting, by locating the recess of one side- 25 plate s on die-plate 49, with shoulder k fitting the periphery of the die at a moment when carriers 31 are retracted by springs 40. The lower shaft and fitting G are moved up bringing the can-flanges opposite the 30 seaming rolls, as shown in Figure 2; and when shaft 48 is an "idler," that is, not positively driven in definite position in relation to shaft 2, a part-rotation of the latter shaft brings its die-plate 49 into reg- 35 istry-engagement with the upper can-side-plate. Shortly thereafter feed cams 10 advance the seaming rolls into engagement with the can-flange-edges. The cam-groove 50, which may be identified in some cases as 40 a master cam, otherwise as a contour-cam, meantime moves slides 24 and carriers 31 in and out in strict accordance with the contour of the can. After a suitable number 45 of rotations of the can carrying shafts, the amount of rotation depending on the ratio of gear-connections between shafts 2 and 9, the inward feed movement of carriers 31 in relation to slides 24 is completed, complet- 50 ing the formation of the can-seams; the car- 55 riers are retracted, the seamed can removed and replaced by another assembly, and so on.

My invention therefore provides means for simultaneously seaming two sides on cans of irregular contour, in a rapid and economical manner.

When the can shape (contour) is changed, a master cam of corresponding contour is substituted for the one shown; also the die-plates 46 and 49 are replaced by others of 60 appropriate form.

Fitting F may comprise a sleeve 70, integral with or attached to cam body 45; and the sleeve may be secured to shaft 2 by a set-screw 71, or other suitable device for 65 the ready detachment of the fitting.

Fitting G may be similarly detachably secured to shaft 48.

Desirably, also, die-plates 46 and 49 are made separate from the bodies of the fittings, and are detachably secured thereto, 70 as, for example, by screws 75, the heads of which are accommodated by suitable countersinks in the plates.

Containers of the class described are often provided with dispensing tops such as t, 75 Figure 4; and these may be applied in some cases after the cans are in other respects completed; but otherwise for convenience or economy in manufacture it may be desirable to secure the dispensing closure in the body- 80 strip b before the sides s are applied. My invention may be adapted to permit the side-seaming operation when the dispensing tops are in place, in certain cases. For instance, in Figures 1 to 3, the seaming rolls provide 85 sufficient clearance to avoid conflict with the closure t of Figure 4.

Containers designed for the purposes de- 90 scribed are usually symmetrical with respect to a certain axis of rotation, as in the case of Figure 4; but this is not necessarily so; for containers having non-symmetrical side outlines can be as easily seamed, since the master cam is in each case made to conform to the can-side contour, and the seaming 95 rolls are compelled to move accordingly.

While the can members s are appropri- 100 ately described as sides, or side-plates, in the case of containers such as above de- 105 scribed, it is evident that where the body di- 110 mension is considerably longer, the mem- bers s would then appear to be ends, rather than sides. Such terms therefore have mainly a relative, and not a limiting significance.

Evidently, from the foregoing descrip- 110 tion, many changes in structure and arrange- 115 ment of parts may be made without depart- 120 ing from the principles of the invention; and I contemplate the employment of all structures which are properly within the 125 scope of the following claims.

What I claim is:

1. In a machine of the class described, means for supporting a container assembly 115 comprising a body and two side members having projecting flanges, a pair of seaming rolls for simultaneously seam-forming the flanges by relative rotation of the assembly and the rolls, means for moving the 120 rolls to and fro in conformity with the as- 125 semby contour, and means for advancing the rolls for progressive seam-formation.

2. In a machine of the class described, means for supporting a container assem- 125 bly of non-circular outline comprising a body and two side members having project- 130 ing flanges, a pair of seaming rolls for sim- 135 ultaneously seam-forming the flanges by relative rotation of the assembly and the rolls,

means for moving the rolls to and fro in conformity with the assembly contour, and means for progressively feeding the rolls in seam-forming contact with the flanges.

5 3. A machine for seaming a can assembly composed of a body and two recessed side plates of irregular contour and having projecting flanges, comprising die plates fitting said recesses, means for rotating the 10 assembly held by the die plates, seaming rolls, one for each of said flanges, means for feeding said rolls in engagement with the flanges to simultaneously seam-form them upon the edges of the body, and means for 15 moving the rolls to and fro in conformity with the assembly-contour.

4. A can seaming machine comprising a vertical spindle rotating in a fixed bearing, a contour cam and a can-face engaging member thereon, a co-axial spindle mounted for rotation and vertical movement, a can-face engaging member thereon, a slide mounted for horizontal reciprocating movement toward and from the spindle axis and having a cam follower engaging the contour cam, a roll yoke mounted for horizontal reciprocating movement on the slide toward and from the spindle axis, a pair of spaced rolls in the yoke arranged to engage projecting edges of the can and seam-form them, a bell-crank pivoted in the slide and engaging the roll yoke, and a vertically moving plunger engaging the bell-crank to impart a feed movement to the yoke while the slide 25 is moved by the contour cam in correspondence with the can contour.

5. A can seaming machine comprising a vertical spindle rotating in a fixed bearing, a contour cam and a can-face engaging member thereon, a co-axial spindle mounted for rotation and vertical movement, a can-face engaging member thereon, a slide mounted for horizontal reciprocating movement toward and from the spindle axis and having a cam follower engaging the contour cam, a roll yoke mounted for horizontal reciprocating movement on the slide toward and from the spindle axis, a pair of spaced rolls in the yoke arranged to engage projecting edges of the can and seam-form them, a bell-crank pivoted in the slide and engaging the roll yoke, a vertically moving plunger engaging the bell-crank to impart a feed movement to the yoke while the slide 30 is moved by the contour cam in correspondence with the can contour.

plunger engaging the bell-crank to impart a feed movement to the yoke while the slide is moved by the contour cam in correspondence with the can contour, and means for 55 adjusting the position of the roll yoke in relation to the bell-crank.

6. A can seaming machine comprising a vertical rotary spindle, a contour cam and 60 a can-face engaging member on said spindle, a co-axial spindle mounted for rotation and vertical movement, a can-face engaging member thereon, opposite slides mounted for horizontal reciprocating movement 65 toward and from the spindle axis and having cam followers engaging the contour cam, roll yokes mounted for horizontal reciprocating movement on the slides toward and from the spindle axis, a pair of spaced rolls 70 in each yoke arranged to engage projecting edges of the can and seam-form them, a bell-crank pivoted in each side and engaging the corresponding roll yoke, and a vertically moving plunger engaging each bell-crank to 75 impart a feed movement to the yoke while the slide is moved by the cam in correspondence with the can contour.

7. A can seaming machine comprising a vertical rotary spindle, a contour cam and 80 a can-face engaging member on said spindle, a co-axial spindle mounted for rotation and vertical movement, a can-face engaging member thereon, opposite slides mounted for horizontal reciprocating movement toward 85 and from the spindle axis and having cam followers engaging the contour cam, roll yokes mounted for horizontal reciprocating movement on the slides toward and from the spindle axis, a pair of spaced rolls in each 90 yoke arranged to engage projecting edges of the can and seam-form them, a bell-crank pivoted in each slide and engaging the corresponding roll yoke, a vertically moving plunger engaging each bell-crank to impart 95 a feed movement to the yoke while the slide is moved by the cam in correspondence with the can contour, and means for adjusting the position of the roll yokes in relation to the bell-cranks.

Signed at city of Baltimore, State of Maryland, this 6 day of Dec., A. D. 1920.

HENRY HERMANI.
